WALTER MYERS, OF BRIDGEPORT, CONNECTICUT, ASSIGNOR TO THE SINGER
MANUFACTURING COMPANY, A CORPORATION OF NEW JERSEY.

ORNAMENTAL-STITCH SEWING-MACHINE.

1,135,959.

Specification of Letters Patent. Patented Apr. 13, 1915.

Application filed April 6, 1914. Serial No. 829,798.

To all whom it may concern:

Be it known that I, WALTER MYERS, a citizen of the United States, residing at Bridgeport, in the county of Fairfield and State of Connecticut, have invented certain new and useful Improvements in Ornamental-Stitch Sewing-Machines, of which the following is a specification, reference being had therein to the accompanying drawings.

10 This invention relates to improvements in embroidery or ornamental stitch sewing machines and has for its object to provide a construction better adapted to the imitating of hand embroidery, commonly termed 15 "Maderia work."

In the accompanying drawings, which form a part of the specification, Figures 1, 2 and 3 are views in front side elevation, plan and rear side elevation, respectively, of the 20 present machine. Figs. 4, 5 and 6, a sectional view of the needle vibrating mechanism including the switch cam carried by the main-shaft, a perspective of the needle 25 vibrating segment lever and a like view of the needle vibrating segment lever carrier, respectively, the latter view including the switch cam follower. Fig. 7 a plan view of the cloth-plate including a removable spur eyelet upon which the work is turned 30 to the action of the needle. Fig. 8, an under side view of the front end portion of the cloth-plate shown in Fig. 7. Fig. 9, a longitudinal central section through the front 35 end portion of Fig. 7, showing the spur eyelet in full lines. Fig. 10, the needle-plate interchangeable with the spur eyelet. Fig. 40 11, a perspective of the cloth holding presser, together with a like view of that portion of its securing mechanism located below the head of the bracket-arm.

Referring to the figures, 1 represents the bed-plate of the sewing machine upon which is mounted the bracket-arm comprising the standard 2 and arm bracket 3, 4 the main- 45 or needle-bar driving shaft provided at its rear end with the hand- or band-wheel 5 and at its opposite end with the take-up cam 6; 7 the sewing needle, 8 the needle-carrying bar operatively connected by the link 9 with 50 said take-up cam, the needle-carrying bar 8 being mounted in suitable bearings formed in the swinging gate 10 journaled on pintle screws, as 11, in a manner common to earlier 55 constructions, 12 the take-up lever, 13 thread tension and 14 the thread controller.

15 represents the lower or looper actuating shaft operatively connected at its rear end by suitable quartering cranks, as 16, with the main-shaft 4, its opposite end being provided with a flange 17 connected by 60 link 18 with the crank 19 carried by the gear-shaft 20 provided with the gear-member 21, operatively connected with a like gear-member 22 carried by the loop-taker driver 23, thus transmitting stitch-forming 65 movements to the loop-taker 24, as in earlier constructions.

25 represents one form of commonly employed switch cam into which tracks a follower 26 journaled in a suitable bearing 27 70 preferably formed integral with the segment lever carrier 28, which latter is provided with a hollow shaft 29 journaled in a suitable bearing 30 formed in the bracket-arm, the rear end of said shaft being provided with a suitably secured collar 31 to hold said shaft against accidental endwise movement.

32 denotes a segment lever provided with a hollow shaft 33 journaled in the hollow 80 shaft 29, a segmental guide-slot 34, arcuate slot 35, notch 36 and spring-controlled plunger 37 provided with a seat 38 which registers with one or the other of the openings 39 or 40 formed in the segment lever carrier 85 28, dependent upon the character of the seam or figure desired.

Into the hollow shaft 33 is slidably mounted a plunger 41 provided at one end with an enlarged oval head 42, its opposite 90 end being threaded to receive the screw 43 whose slotted head 44 is arranged on the side of the dividing wall 45, formed integral with the shaft 33, opposite to that of its threaded end, thus permitting endwise 95 movements of said plunger of substantially the length of the body portion of said screw, a spring 46 confined between said slotted head and the screw 47, acting to hold the plunger 41 in its outward position as shown 100 in Figs. 2 and 4.

49 denotes a sleeve secured by screw 50 to the rear end of the hollow shaft 33, and between the enlarged portion 51 of said sleeve and the collar 31 carried by the shaft 10 29 is confined the spring 52 which normally acts to hold the segment lever 32 in operative relation with its carrier 28, for a purpose later to be explained. 53 represents a bracket secured by screws, as 54, to the 10 110

bracket-arm, 55 a rock-shaft journaled in suitable bearings formed in said bracket and onto said shaft is mounted to move endwise, a yoke 56 provided with a crank-arm 57 carrying a cam-plate 58, said yoke being secured to turn with said shaft by a teated screw 59 threaded into said yoke and entering a suitable slot (not shown) formed into said shaft, a cam lever 60 pivoted on a suitable pin (not shown), passing through said shaft, acting in opposition to the resiliency of the spring 61 to move said yoke toward the rear side of the machine, thus carrying said cam-plate out of effective relationship 10 with the head 42 of the plunger 41, for a purpose later to be explained.

62 represents an oscillating shaft crank suitably secured upon the shaft 55 and at its free end provided with a stud-screw 63 20 which tracks a slot 64 formed in the segment lever slide connection 65, the lower end of the latter being provided with a suitable opening (not shown) through which extends a stud 66 threaded into the slide block 25 67 tracking the segmental guide-slot 34, said stud also acting as the pivotal connection for one end of the swinging gate connection 68, the opposite end of the latter being pivotally connected to the swinging gate 10 by a 30 suitable ball joint connection 69.

70 represents a segmental slide block stop adjustably secured in the guide-slot 34, the wing nut 71, threaded onto the stud 66, acting to secure the slide block 67 in given adjustment when it is desired to effect successive zigzag stitches of a given amplitude of needle vibration, a spring 72 attached at one end to the shaft crank 62 and at its opposite end to the connection 65 acting to normally 40 hold the stud 68 at the lower end of the slot 64.

73 represents a thread tension releasing crank-arm suitably secured to the rock-shaft 55, said crank-arm, together with the shaft 45 crank 62, acting to secure said shaft against accidental endwise movement, the crank arm being provided with a depending cam lug 74 which, when depressed, acts on the end of the tension stud 75 to move the latter in operation to the resiliency of the flat spring 76 and coiled spring 77, thus lessening the degree of tension exerted by said latter spring on the tension disks, as 78.

To the front end of the crank-arm 73 is 55 pivotally attached one end of a link 79 whose opposite end is pivotally attached to a rock-lever 80 journaled on a stud 81 threaded into the arm bracket, and to the opposite end of said rock-lever is pivotally attached, by 60 stud-screw 82, a hub 83 into which is threaded the upper end of a treadle-actuated rod 84 which, in practice, is operatively connected with a suitable treadle (not shown), a spring 85 acting to normally hold, through the connections previously pointed out, the axis of

the stud 66 in alinement with the axis of the hollow shaft 33.

86 represents the cloth-plate secured upon the bed-plate 1 by pin 87 and catch lever 88, the free end 89 of the latter underlying the bed-plate, as shown in Fig. 8, when in position to secure said cloth-plate against accidental displacement.

90 denotes a spur eyelet provided with the spur 91, slot 92 and annular groove 93, and when mounted in the cloth-plate, as shown in Figs. 7, 8 and 9, is held against accidental movement by the pin 94 secured in said cloth-plate, the forked end of the sliding plate 95 acting to hold said spur eyelet 90 against accidental displacement with respect to said cloth-plate.

96 denotes a needle-plate interchangeable with, mounted and secured in the same manner as the spur eyelet 90.

97 represents a spring depressed hollow cloth presser carrying bar into which is mounted a rod 98 threaded at its upper end to receive the nut 99 and at its opposite end threaded into an enlarged extension 100 provided with oppositely arranged walls, as 101, and gripping jaws, as 102, which latter are arranged slightly below the lower end of said cloth-presser carrying bar. 103 denotes the cloth-presser provided with the spur opening 104 and slot 105, the latter, in practice, embracing the walls 101, the nut 99 acting to raise the rod 98 and grip the oppositely arranged surfaces adjacent to said slots between the lower end of the cloth-presser carrying bar and the gripping jaws 102, thus securing the cloth-presser in effective relationship with the fabric being acted upon.

In the use of sewing machines for effecting embroidery work much depends upon the operator and the object in providing improved stitch controlling means, as herein, is not only to lessen the responsibility of the operator but to effect an improved and increased product, and for a better understanding of the advantages of the present improved means different operations will be chiefly described commencing with the stitching of embroidery eyelets.

As previously pointed out, the present construction comprehends the employment of interchangeable spur eyelets and needle-plates, the former including different sizes of spurs to meet the requirements of different sizes of perforations in the fabric. Supposing the spur eyelet 90 to represent the desired size the operator adjusts the fabric with the spur in the perforation and adjusts the cloth-presser down upon the fabric when, if it is desired to stitch an eyelet of uniform radial stitches, the operator adjusts and by winged nut 71 secures the slide 34 to effect the desired amplitude of vibration of the needle, and during the stitching operation the fabric is manually turned about the

spur for one, two or more rotations dependent upon the desired character of product, and at the completion of the formation of the radial stitches the operator moves the cam-lever 60 to its vertical position, thus permitting the spring 61 to move the cam-plate 58 in line with the head 42 of the plunger 41 when the operator, through the manipulation of a suitable treadle, rocks the shaft 55 which causes the cam-plate 58 to move the plunger 41, and through the medium of spring 46 and nut 47, move the segment lever toward the operator a distance sufficient to release the teat 38 from engagement with the opening 40 and with the stationary lug 106 in engagement with the notch 36 formed in said segment-lever, thus holding the latter out of engagement with the segment lever carrier and with the needle 20 in its outside or depth stitch position or in position to form either superposed tying stitching or a circular line of stitches about the eyelet in line with the depth stitches, after which the operator returns the lever 60 to its former position, it being understood that radial stitches of varying lengths may be employed through the manipulation of a suitable treadle connected, as previously described, with the rock-shaft 55. It being understood that the spring 46 when depressed is of sufficient strength to overcome the strength of the spring 52.

When it is desired to do flat embroidery the spur eyelet is exchanged for a needle-plate and the cloth-presser removed, the fabric being held in one form of commonly employed tambour frame which is manually held down upon the cloth-plate, and as in stitching eyelets, the fabric is manually presented to the action of the needle. In effecting the last mentioned embroidery the teat 38 is transferred from the opening 40 to the opening 39, thus carrying the segment lever 32 and needle 7 to the left of their former positions which causes the needle, when forming zigzag stitches, to be moved laterally equi distant across the axis of the previously positioned spur 91 when, through the means previously described, the operator moves the slide 67 in the guide-slot 34 to such position as will effect the desired design or figure, the tying off or binding stitches being effected by allowing the slide 67 to position the axis of the stud 66 in alignment with the axis of the shaft 33, and during the manual manipulation of the slide 67 the cam lug 74 is caused to release the tension action of the disks 77 more or less dependent upon the amplitude of vibration of the needle, the tension device 13 acting uniformly upon the thread during the stitching operation.

The lug 107 of the segment lever carrier 28 tracks the slot 35 formed in the segment lever 32 and acts to limit the downward

movement of the slide 67 when effecting radial stitches as in the stitching of an eyelet, but when the teat 38 of the plunger 37 occupies the opening 39 in the lever 28 the guide-slot 34 is carried to the left of said lug thus permitting said slide to be moved below said lug as when effecting flat embroidery, the stop 70 determining the limit of downward movement of the slide 67.

Having thus set forth the nature of the invention, what I claim herein is:—

1. In a machine for ornamental stitching, the combination with a stitch-forming mechanism including a laterally movable needle-carrying bar, of a manually controlled rock-shaft, a yoke carried thereby and provided with means for controlling the relative arrangement of the successively formed stitches, said rock-shaft being provided with means for controlling the amplitude of the lateral movements of said needle-bar independently of the means for controlling the relative arrangement of the successively formed stitches. 80

2. In a machine for ornamental stitching, the combination with a stitch-forming mechanism including a laterally movable needle-carrying bar, a stationary cloth-plate into which is removably secured a plate provided with an elongated needle opening, of a manually controlled rock-shaft, a yoke carried thereby and provided with means for controlling the relative arrangement of the successively formed stitches, said rock-shaft being provided with means for controlling the amplitude of the lateral movements of said needle-bar independently of the means for controlling the relative arrangement of the successively formed stitches. 95

3. In a machine for ornamental stitching, the combination with a stitch-forming mechanism including a laterally movable needle-carrying bar, and a cloth-presser mechanism including a cloth-presser and a tubular cloth-presser bar into which is slidably mounted a holding bar provided at its lower end with gripping jaws, its opposite end being threaded and provided with a nut acting to force said jaws toward the lower end of said cloth-presser bar and hold said cloth-presser against accidental displacement, of a manually controlled rock-shaft, a yoke carried thereby and provided with means for controlling the relative arrangement of the successively formed stitches, said rock-shaft being provided with means for controlling the amplitude of the lateral movements of said needle-bar independently of the means for controlling the relative arrangement of the successively formed stitches. 105 110

4. In a machine for ornamental stitching, the combination with a stitch-forming mechanism including a laterally movable needle-carrying bar and a cloth-plate provided with a removable plate for supporting the fabric 115 120 125 130

directly about the lines of needle actuation, of a manually controlled rock-shaft, a yoke carried thereby and provided with means for controlling the relative arrangement of the successively formed stitches, said rock-shaft being provided with means for controlling the amplitude of the lateral movements of said needle-bar independently of the means for controlling the relative arrangement of the successively formed stitches.

5. In a machine for ornamental stitching, the combination with a stitch-forming mechanism including a laterally movable needle-carrying bar and a cloth-plate into which is removably mounted a plate provided with a fabric spur, of a manually controlled rock-shaft, a yoke carried thereby and provided with means for controlling the relative arrangement of the successively formed stitches, said rock-shaft being provided with means for controlling the amplitude of the lateral movements of said needle-bar independently of the means for controlling the relative arrangement of the successively formed stitches.

6. In a machine for ornamental stitching, the combination with a stitch-forming mechanism including a laterally movable needle-carrying bar, of a manually controlled rock-shaft, a yoke carried thereby and provided with means for controlling the relative arrangement of the successively formed stitches, said rock-shaft being provided with means for controlling the amplitude of the lateral movements of said needle-bar independently of the means for controlling the relative arrangement of the successively formed stitches, the means for controlling the amplitude of vibration of the needle-carrying bar including a segment lever and segment lever carrier, the latter provided with means for limiting the amplitude of vibration of said needle-carrying bar when forming stitches about a given axis.

7. In a machine for ornamental stitching, the combination with a stitch-forming mechanism including a laterally movable needle-carrying bar, of a manually controlled rock-shaft, a yoke carried thereby and provided with means for controlling the relative arrangement of the successively formed stitches, said rock-shaft being provided with means for controlling the amplitude of the lateral movements of said needle-bar in-

dependently of the means for controlling the relative arrangement of the successively formed stitches, the means for controlling the amplitude of vibration of the needle-carrying bar including a segment lever carrier and segment lever, the latter provided with means for limiting the amplitude of vibration of said needle-carrying bar when forming successive zigzag stitches arranged in straight and curvilinear directions.

8. In a machine for ornamental stitching, the combination with a stitch-forming mechanism including a laterally movable needle-carrying bar, and multiple needle thread tension devices, of a manually controlled rock-shaft provided with means for controlling the amplitude of the lateral movements of said needle-bar and with means for changing the degree of tension exerted by one of said tension devices to meet the requirements of the changes in the amplitude of the lateral movements of said needle-bar and, a yoke carried by said rock-shaft and provided with means for controlling the relative arrangement of the successively formed stitches.

9. In a machine for ornamental stitching, the combination with a stitch-forming mechanism including a laterally movable needle-carrying bar, of a manually controlled rock-shaft, a yoke provided with means for controlling the relative arrangement of the successively formed stitches, said rock-shaft being provided with means for controlling the amplitude of the lateral movements of said needle-bar independently of the means for controlling the relative arrangement of the successively formed stitches, the means for controlling the amplitude of lateral movement of the needle-carrying bar including a segment lever carrier having a hollow shaft journaled in the sewing machine bracket-arm, a segment lever depending from a shaft journaled on said hollow shaft and means including a manually controlled plunger and opposing spring for moving said segment lever out of operative relationship with said segment lever carrier.

In testimony whereof, I have signed my name to this specification, in the presence of two subscribing witnesses.
